SERVING BAR DISPENSER FOR HIGHBALL STIRRER STICKS

George Neumann and Adolph Patzke,
Milwaukee, Wis.

Application October 23, 1951, Serial No. 17,078

Term of patent 14 years

(Cl. D2—3)

To all whom it may concern:

Be it known that we, George Neumann and Adolph Patzke, citizens of the United States, residing at Milwaukee, in the county of Milwaukee and State of Wisconsin, have invented a new, original, and ornamental Design for a Serving Bar Dispenser for Highball Stirrer Sticks, of which the following is a specification, reference being had to the accompanying drawing, forming part hereof.

Figure 1 is a perspective view showing our new design for a serving bar dispenser for highball stirrer sticks, looking toward the front and one end wall.

Figure 2 is a similar view but looking toward the rear and the other end wall.

We claim:

The ornamental design for a serving bar dispenser for highball stirrer sticks, substantially as shown.
